UNITED STATES PATENT OFFICE

JOHN LISTER, OF LONDON, ENGLAND, ASSIGNOR TO THE EVER READY COMPANY (GREAT BRITAIN) LIMITED, OF LONDON, ENGLAND

ELECTRIC TORCH

Application filed July 25, 1929, Serial No. 380,806, and in Great Britain April 15, 1929.

This invention consists in improvements in or relating to electric torches especially adapted for use in inflammable atmospheres including petrol vapours.

5 According to the present invention, a torch comprises a battery-container which is completely closed in a gas-tight manner, which has at least one gas-tight removable cap for the insertion and removal of the battery and 10 which has a switch whereof the movable member is available from outside the torch, but extends into the casing also in a gas-tight manner.

Preferably, the movable switch-element 15 passes through the removable cap and a second removable and gas-tight cap is also provided for giving access to the lamp bulb.

In one preferred embodiment of the invention each cap that is removable has means 20 for enabling it to be locked in place against unauthorized removal.

In order that the invention may be more clearly understood, two preferred examples thereof will now be described with the aid 25 of the accompanying drawings, in which—

Figure 1 is a perspective external view of one form seen from the switch end;

Figure 2 is a central longitudinal section of the torch shown in Figure 1;

30 Figure 3 is a section on the line 3—3 of Figure 2;

Figure 4 is a perspective external view of a second form seen from the lamp end;

Figure 5 is a side elevation of the torch 35 shown in Figure 4, partly in section;

Figure 6 is a sectional view on an enlarged scale of a detail of the cap-locking means for the constructions shown in Figures 4 and 5;

40 Figure 7 is an illustration of the key required for manipulating the locking means shown in Figures 4 to 6;

Figure 8 is an enlarged sectional detail 45 of parts of the torch shown in Figures 4 and 5; and

Figure 9 is a perspective view of a detail, showing the formation of the end of the casing 10 employed in the construction illustrated in Figures 4, 5 and 8.

Like reference numerals indicate like parts in the several figures of the drawings.

In the first example, illustrated in Figures 1 to 3, the casing 10 is cylindrical, is formed with outwardly-extending flanges 11 inset slightly from each end, and is open at both ends. The two ends of the casing which extend beyond the flanges 11 are both screw-threaded to engage correspondingly threaded portions of end-closure caps 13 and 14 respectively, each of which is formed with a flange 15 which, when the cap is screwed into place, as shown in Figures 1 and 2, lies over the flange 11 on the appropriate end of the casing.

The end-cap 13 is itself open-ended, and in the outer end there is secured a cover-glass 16, preferably of nonsplinterable or ply-glass, and behind the latter there is a lamp-reflector 17. The latter is centrally perforated to 70 pass over the incandescent electric lamp bulb 18 which is carried in a socket 19 formed in an insulating block 20 secured in the adjacent end of the casing 10.

The socket 19 is a metal one which is electrically connected to the casing by means of a metal strip 21 that is formed integral with or is otherwise metallically connected to the socket 19 and is also riveted to a lug 22 that extends inwardly from a ring 23 that is itself metallically connected to the casing 10. For instance, the ring 23 may be either a tight-jamming fit in the casing 10, or it may be soldered or otherwise metallically connected thereto. The lamp bulb 18, in this 80 case, is intended to have a central terminal 24 which, when the bulb is screwed into place in the socket 19, will engage a conducting strip 25, also carried on the insulating block 20. One end of the strip 25 is secured in a close metallic contact between one end of a bridge-member 26 and the insulating block 20, and both ends of the bridge-member 26 are riveted to the insulating block. The free 85 end of the strip 25 will press resiliently against the electrode 24 so as at all times to maintain good electrical contact therewith.

The other terminal of the lamp bulb filament is constituted by the screwed metal cap 27 which seats in the socket 19.

One pole 28 of a cylindrical battery 29, when the latter is inserted within the casing, will engage the bridge-member 26 and so be in electrical contact with the terminal 24 of the lamp. Electrical contact between the other pole of the battery and the metal cap 27 of the lamp is made through the casing 10 and through a switch that is located in the end of the casing that is closed by the cap 14.

10 The end-cap 14 has a closed outer end-wall 30 formed with a screwthreaded central aperture through which passes a screwed pin 31 terminating at its outer end in a knurled head 32. At its inner end the pin 31 has a portion 33 of reduced diameter which is also screwthreaded and receives upon it a nut 34 which is screwed down on to the shoulder formed at the junction of the parts 31 and 33 so as to leave the extremity of the part 33 exposed beyond it. The nut 34 is in the form of a flat disc which is guided in a sleeve portion 35 formed integrally with the inner surface of the end-wall 30 of the cap 14.

Slidably fitted within the end of the casing 10 adjacent the cap 14 is a hollow cylindrical block 36 of insulating material on which is mounted the usual tapering coiled spring 37, the inner end of which presses against the exposed metallic end of the battery 29 constituting the second pole thereof.

The other end of the spring is secured between one head of a screw-bolt 39 and a metal plate 38 which is held to the face of the insulating block by means of the screw-bolt 39.

25 The other head 40 of this bolt appears centrally on the inner face of the insulating member 36 and is presented towards the extension 33 of the screw-pin 31. As will be seen from the drawings, the concavity of the hollow block 36 is presented towards the screwed pin 31 so that when the block 36 is forced, by pressure of the spring 37, against the inner face of the end-wall 30 of the cap 14, the contact-stud (or bolt-head) 40 in the

block will be maintained out of engagement with the extension 33 of the screwed pin 31 when the latter is withdrawn, for example to a position in which the nut 34 is drawn against the inner face of the end-wall 30.

50 By manipulating the pin 31 by turning it one way or the other so as to advance or withdraw it from the contact-stud 40, it can be brought into and out of engagement with that stud, thereby making, or breaking, respectively, the battery circuit.

The flanges 11 and 15 at the two ends of the casing have each of them a series of holes 41 formed in them so that after the caps have been screwed into position there will be at least one hole in a cap-flange 15 which will be in register with a hole in a casing-flange 11. Wires, such as 42, may be passed through these registering holes and officially sealed as at 43 so that the caps cannot be removed by an unauthorized person. In Figure 1 a locking

wire and seal have been shown at one end of the casing only, but it will be appreciated that similar locking means will be employed for both ends when the torch is in use. The cap 13, carrying the reflector, can be adjusted before the locking or sealing wire is applied to give the desired focussing, but thereafter further focussing will be impossible by the user unless he is the person authorized to remove the seal.

70 In the second example illustrated in Figures 4 and 5, the construction of the casing, lamp socket, and switching means, is substantially identical with that of the corresponding parts described above in connection with Figures 1 to 3, with the exception that the circular flanges 11 and 15 are dispensed with. In Figures 4 and 5, the end-caps are each locked in position by means of a screw-bolt 50 which is screwthreaded into a socket 51 that is formed as a radial projection extending from the cap with the axis of the socket parallel with the axis of the casing. The inner end of the screw-bolt 50 is intended to be received in a corresponding socket 52 formed also as a radial projection from that part of the casing which is adjacent the cap, and the screw-bolt itself is such that it can be actuated only by means of a small key insertable through an aperture in the outer end of the socket 51. This is ensured by making the length of the screw-bolt 50 such that when it is screwed home the level of its head will be well within the screwthreaded recess in the socket 51. In order that the bolt 50 shall not be entirely withdrawn from the socket 51, a shouldered portion 53 is provided at the end of the socket 51 to engage with the outer end of the bolt 50. The bolt 50 will be inserted within the socket 51 from its inner end before the parts are assembled.

90 The cap 13 in this second example of the invention is of considerably larger diameter than that of the casing 10 and is secured by means of a screwthread on to the outer end of a spherically formed part 54, the inner end of which is formed with a cylindrical sleeve 55 which is screwthreaded on to the end of the casing 10 and is so formed that it cannot be entirely withdrawn therefrom. The reflector 17 is pressed against the outer end of the part 54 by the cap 13 and the latter, together with the part 54 and its reflector, is capable of endwise adjustment by means of the screwthreaded connection between the sleeve 55 and the body 10 of the casing in order to permit of focussing the beam of light at will by the user of the torch after the end-caps 13 and 14 have been locked in position.

95 The manner in which the cylindrical sleeve 55 is screwthreaded on to the end of the casing 10 so that it is adjustable but not detachable therefrom, is illustrated in detail in Figures 8 and 9. As shown in these figures, the

end of the casing 10 is screwthreaded at 110. Four lugs 111 are produced by sawcutting inwardly in a direction parallel to the axis of the casing 10, and these lugs are formed with 5 overhanging shoulders 112 which are produced by cutting a groove 113 first of all throughout the whole periphery of the end of the casing 10 beyond the end of the screw-thread 110. The lugs 111 are then bent inwardly, as is shown in the case of the two lugs on 10 the right-hand side of Figure 9. The shoulder portions equivalent to 112 which would have been present on the sectors between the lugs 111, are, after the latter have been bent 15 inwardly, cut away from the end of the casing 110. The sleeve 55 is then screwthreaded on to the end of the casing 10, and the lugs 111 are then forced outwardly into the position shown in the left-hand side of Figure 9 20 and in Figure 8. The outer end screwthread on the casing 55 can therefore be brought into contact with the shoulders 112, but not beyond, and by this means the sleeve 55 can be moved in both directions for a limited amount 25 without being completely removable from the end of the casing 10. The hemispherical part 54 is secured at 154 by brazing or the like to the end of the sleeve 55 so that the part 30 54 is adjustable in an axial direction with the sleeve 55. As the reflector 17 is movable with the hemispherical portion 54, the beam of light from the bulb 18 can, by this means, be focused.

I claim:—

35 1. An electric torch comprising in combination a battery container which is completely closed in a gas-tight manner, a gas-tight removable end-cap giving access to the interior of the container, a lamp socket with- 40 in the container near said end-cap, a reflector carried by said end-cap, a switch whereof a movable switch member is available from the outside of the torch but extends into the interior thereof in a gas-tight manner, lock- 45 ing means for preventing unauthorized removal of the end-cap, means for permitting endwise movement of the reflector along the torch for focussing the beam of light at will after the end-cap has been locked in position, 50 and at least one stop for permitting only a limited endwise movement of the reflector along the torch and for preventing the parts from being separated until the container is 55 opened, otherwise than by removal of end- cap.

2. An electric torch comprising in combination a tubular battery container which is completely closed in a gas-tight manner, a lamp socket within the container, two gas-tight removable end-caps, one of which 60 serves for the insertion and removal of the battery, and the other affords access to the lamp-socket and carries a reflector, a switch whereof a movable switch member is avail- 65 able from the outside of the torch but ex-

tends into the interior thereof also in a gas-tight manner, locking means for preventing unauthorized removal of the end-caps, means for permitting endwise movement of the reflector along the torch for focussing the beam 70 of light at will after the end-cap has been locked in position, and at least one stop for permitting only a limited endwise movement of the reflector along the torch and for preventing the parts from being separated until 75 at least one of the end-caps is removed.

3. An electric torch comprising in combination a tubular battery container having screw-threaded extremities and open only at both extremities, two end-closure caps having a screw-threaded engagement each with its end of the tubular container, a lamp socket situated within one end of the container, a reflector carried by the lamp at that end and adjustable with the cap relatively 80 to the socket, a switch member comprising a screw-threaded pin passing through the other end-cap at the opposite end of the container and having a head available from the outside of the end-cap for manipulating the pin, radial projections on the casing adjacent the inner end of each cap, radial projections on the said caps which when the latter are in position will be opposed to those on the casing, cooperating apertures in the said 85 pairs of projections for the reception of locking means whereby the caps are locked to the container against unauthorized removal, and at least one stop for permitting only a limited endwise movement of the reflector 90 along the torch, and for preventing the parts from being separated until at least one of the end caps is removed.

In testimony whereof I affix my signature.
JOHN LISTER.
